E. S. LANDIS

SIDEBOARD BRACKET

Filed Jan. 24, 1923

Lev Hayes

WITNESS:

Earl S. Landis
INVENTOR
BY *Victor J. Evans*

ATTORNEY

UNITED STATES PATENT OFFICE.

EARL S. LANDIS, OF MONROE, INDIANA.

SIDEBOARD BRACKET.

Application filed January 24, 1923. Serial No. 614,629.

To all whom it may concern:

Be it known that I, EARL S. LANDIS, a citizen of the United States, residing at Monroe, in the county of Adams and State 5 of Indiana, have invented new and useful Improvements in Sideboard Brackets, of which the following is a specification.

This invention relates to structural elements of farm wagons and has for its object 10 the provision of a novel side board bracket for grain body attachments for hay racks and the like.

An important object is the provision of a bracket of this character designed to be used 15 for detachably mounting side boards upon the sills of a hay rack, the bracket being of such construction that it includes a movable portion which when moved to released or inoperative position will permit the side 20 boards to be removed, the device entirely obviating the use of any bolts or other securing devices of a similar nature.

An additional object is the provision of a device of this character which will be simple and inexpensive in manufacture, highly 25 efficient in use, durable in service and a general improvement in the art.

With the above and other objects and advantages in view the invention consists in 30 the details of construction to be hereinafter more fully described and claimed and illustrated in the accompanying drawings, in which:

Figure 1 is a perspective view of a hay 35 rack equipped with side boards having my brackets thereon, the side boards being illustrated as held in their proper or operative relation,

Figure 2 is a detail perspective view on a 40 larger scale showing one of the bracket members in its operative position and

Figure 3 is a perspective view of a portion 45 of the hay rack showing one of the bracket members, the bracket member being illustrated as swung into inoperative or released position to permit removal of the side boards.

Referring more particularly to the drawings the letter A designates the frame or bed 50 or a hay loader which includes the usual longitudinal supports B, transverse bars C, floor D and side sills E. To this structure it is desired to attach the side boards F.

In carrying out my invention I provide 55 at each side of the hay rack a plurality of holding devices which include portions car-

ried by the side boards and other portions co-acting therewith and carried by the sills. The structure carried by the side boards consists of an elongated upright plate like 60 body 10 bolted or otherwise secured onto the side boards and formed or otherwise provided with spaced bearings 11. The lower end of the member 10 terminates in an upturned hook 12. The hooks 12 are designated 65 to engage within eye bolts 13 which pass through the sills E. The numeral 14 represents the movable portion of the device which is formed in the nature of an angle 70 brace and which has its vertical portion 15 terminating in trunnions 16 pivoted within the bearings 11. The lower, inner or rear corners of the braces 14 are cut away as shown at 17 for the accommodation of the hooks 12 and eye bolts 13 engaged thereby 75 while the outer or front corners 18 constitute foot members designed to bear upon the sills.

In installing my invention, the sills E are equipped with the eye bolts 13 arranged at suitable spaced intervals. The side boards 80 have secured thereto the members 10 and parts carried thereby. In mounting the side boards upon the rack, it is first necessary to swing the braces 14 flat against the side boards as shown in Figure 3, whereupon the 85 side boards may be tilted sufficiently that the hooks 12 will enter the eye bolts, after which the side boards are brought into upright position and the braces 14 are swung to extend outwardly at right angles to the side 90 boards, the foot portions 18 bearing upon the sills E as most clearly shown in Figure 2. In removing the side boards the reverse operation is followed.

From the foregoing description and a 95 study of the drawings it will be apparent that I have thus provided a simply constructed and consequently inexpensive bracket device for detachably mounting and yet rigidly holding side boards upon a hay 100 rack or the like for the purpose of converting the same into a wagon structure suitable for carrying grain and the like. It is to be noted that it is unnecessary to use any nuts, bolts or the like when placing the side 105 boards in position or removing them as the case may be, the operation being thus extremely simple and requiring no skill.

While I have shown and described the preferred embodiment of the invention it is 110 of course to be understood that I reserve the right to make such changes in the form,

construction and arrangement of parts as will not depart from the spirit of the invention or the scope of the subjoined claims.

Having thus described my invention I claim:

1. A bracket device for detachably mounting side boards upon a hay rack for the purpose of forming a wagon body, comprising supporting members secured upon the outer side of each side board and formed with hooks, eye bolts carried by the sills at the sides of the hay rack and within which said hooks are engageable, and brace members pivoted upon said supports and swingable to extend at right angles thereto bearing upon the sills.
2. A bracket device for detachably mounting side boards upon a hay rack for the purpose of forming a wagon body, comprising supporting members secured upon the outer side of each side board and formed with hooks, eye bolts carried by the sills at the sides of the hay rack and within which said hooks are engageable, and brace members pivoted upon said supports and swingable to extend at right angles thereto bearing upon

the sills, the supporting members being formed with spaced bearings, and the brace members being formed with upper and lower trunnions revolvably engaged within said bearings.

3. A bracket device for detachably mounting side boards upon a hay rack for the purpose of forming a wagon body, comprising supporting members secured upon the outer side of each side board and formed with hooks, eye bolts carried by the sills at the sides of the hay rack and within which said hooks are engageable, and brace members pivoted upon said supports and swingable to extend at right angles thereto bearing upon the sills, the supporting members being formed with spaced bearings, and the brace members being formed with upper and lower trunnions revolvably engaged within said bearings, and the lower corners of the braces nearest the supports being cut away for the accommodation of said hooks and the eye bolts engaged thereby.

In testimony whereof I affix my signature.

EARL S. LANDIS,
